INERTIA AND AIR-OPERATED ARMING MECHANISM

Jacob Rabinow, Laurence M. Andrews, and John W. Bowling, Washington, D. C., assignors to the United States of America as represented by the Secretary of the Army

Application January 15, 1948, Serial No. 2,533

8 Claims. (Cl. 102—81.2)

(Granted under Title 35, U. S. Code (1952), sec. 266)

The invention described herein may be manufactured and used by or for the Government, for governmental purposes, without the payment to us of any royalties thereon.

This invention relates to an arming mechanism for an electric fuze for ordnance projectiles, such as rockets, and has for its primary object to insure that the fuze can not be armed unless the projectile bearing it has been discharged normally.

Among the objects of the invention is the provision, in a powder train interrupter of the out-of-line type, of means for aligning the detonator only after the completion of normal acceleration resulting from successful discharge of the projectile. Another object is to provide safety means including an arming wire for the fuze so arranged that accidental withdrawal of the arming wire can not arm the fuze. Still another object is to provide means requiring both air pressure and inertia forces to accomplish arming of the fuze. More specifically this object is accomplished by the use of disengaging gears so arranged that arming is initiated and partly accomplished by means of a propeller, and is completed by means of a spring.

The purpose of these elements is to provide a projectile fuze which is fool-proof as possible in that it requires a series of conditions to arm the fuze, which conditions occur only if the fuzed projectile has been safely handled and successfully discharged. This is particularly important in the case of extra-sensitive fuzes such as super-quick fuzes or proximity fuzes.

Other objects and advantages of our invention will become apparent as the disclosure proceeds.

In the drawings:

Fig. 1 is a longitudinal axial partial sectional view of the nose of a projectile embodying our invention, prior to discharge.

Fig. 2 is a similar view after the projectile has been discharged.

Fig. 3 is a sectional transverse view taken on line 3—3 of Fig. 1.

Fig. 4 is a sectional transverse view taken on line 4—4 of Fig. 2.

Fig. 5 is a longitudinal sectional detail taken on line 5—5 of Fig. 3, and

Fig. 6 is a longitudinal sectional detail taken on line 6—6 of Fig. 4.

Fig. 7 is a detail view of the bottom plate showing the gear sector in the final armed position.

Referring to Fig. 1, the fuze 1 is screwed into the projectile 8 which may be a rocket mounted on an airplane for discharge therefrom against another airplane or a ground target, or it may be any other type of projectile intended to be discharged with high initial acceleration toward a target. Fuze 1 is provided with an air-operated wind vane or turbine 2 which on travelling through the air tends to drive a shaft 2A which, in turn, (under the proper operating conditions) drives a gear

train contained within the section 3 of the fuze which also contains the inertia mechanism of our invention. When the gear train is effectively driven by the shaft at a relatively high speed, it turns arming shaft 16 which carries the detonator rotor 4 with it due to lock pin 6, which at all times keys rotor 4 to shaft 16. Initially the detonator rotor 4 is so oriented that squib 5 is safely out of line with port 5C and contacts 5A and 5B of the squib firing circuit are similarly out of line. When the arming device is successfully operating, i. e., when normal discharge occurs, the elements above described will be effective to rotate the squib 5 from the safety position shown in Fig. 1 to the armed position in which the squib is aligned with elements 5C and 5B so that closing of the squib circuit by electric fuze means of any suitable type such as a proximity fuze, electric time fuze, etc., will be effective to cause a detonation. The electric fuze elements are not shown in the drawings but the components thereof are intended to be housed in the empty spaces shown immediately before and behind the mechanism 3 in Fig. 1. Because of the stringent safety requirements of proximity fuzes, our invention is particularly useful with such fuzes and is especially adapted for use with one type of proximity fuze in which the high speed shaft 2A drives an electric generator for energizing the fuze, since this source of power can then be also used to drive our safety arming mechanism. An arming wire 7 is normally threaded through a suitable bracket 7A on the body of the fuze, and through the vane 2 so as to keep the latter from turning until the projectile 8 is fired, at which time the arming wire is withdrawn.

The main elements of the gear train and inertia mechanism are contained between two flat plates 27 and 28 which are spaced by studs 26. Worm 29 on the end of shaft 2A drives gear 10 which, in turn, through worm 11 (Fig. 4) drives gear 12. Gear 12 is mounted integrally with pinion 13 which drives idler 14 loosely mounted on stud 14A. Idler 14 is initially engaged with the teeth of gear sector 15 (Fig. 3). This gear sector 15 is rigidly attached to shaft 16 for rotation therewith.

The initial condition of the mechanism is of course the safe or unarmed condition which is shown in Figs. 1, 3 and 5. A detent element 24 (Fig. 3) is mounted so as to pivot loosely on the stud 26, and is provided with a notch 23. A setback weight 20 is preferably formed of two semi-circular plates riveted together at 20A and is provided with struck-out portions 20B serving as hinge pins in cooperation with coacting struck-out portions of plate 27 (Fig. 2) whereby the weight 20 has a limited amount of angular motion about the axis of its hinge pins between two extreme positions shown in Figs. 1 and 2 respectively. Weight 20 is biased into the forward position shown in Figs. 1 and 5, by a compression spring 21, the lower end of which engages plate 28 (Fig. 5) while the upper end is seated in a depression in weight 20. Weight 20 is provided with a finger 22 (see for example Fig. 6) which engages notch 23 of detent 24 in such fashion that when the weight 20 is in its initial position detent 24 is in the path of gear sector 15, as shown in Fig. 3, and serves as a stop for sector 15, but when weight 20 is displaced to its rearward position as by acceleration forces acting thereon, detent 24 is moved by finger 22 to the position shown in Fig. 4, allowing gear sector 15 to move into the position shown in Fig. 4.

If the arming wire 7 were accidentally pulled so as to release the vane 2 while the projectile, for example, a rocket, is mounted below a wing of an airplane, the vane would start turning, resulting in the rotation of gear sector 15, clockwise, as seen in Fig. 3, and the gear will be driven until it impinges on detent 24. Any further turning of the vane would then either be prevented or

3

else a mechanical failure of the gear train would result due to the large mechanical advantage of the system.

If, however, the projectile were properly fired immediately after the arming wire is pulled, acceleration of the fuze body would cause weight 20 to move back compressing spring 21 and moving detent 24 outwardly as shown in Fig. 4. Rotation of the vane 2 under this condition would permit the gear sector teeth to move clockwise without hitting detent 24 until they were completely disengaged from the driving idler 14. A spring 18 is mounted around shaft 16 and fastened thereto at 18A (Fig. 6) at one end and hooked into plate 28 at the other end at 18B so as to drive the shaft 16 and sector 15 clockwise in the same direction as turned by the action of the vane 2. Spring 18 causes the gear sector 15 to continue its motion after it is disengaged from the driving idler 14 and drives it forward until the leading edge of the gear sector impinges on detent 25 (Fig. 4) which extends from weight 20 similar to finger 22 (see Figs. 1 and 2). Shaft 2A is now free to continue rotation but further rotations of the shaft 2A has no effect on the arming system.

The arming mechanism has now rotated the arming rotor 4 approximately 90° to the position shown in Fig. 6. This is not sufficient for arming as another 90° of rotation is necessary for the squib to be properly aligned into firing position. However, it is desirable that the fuze be not fully armed until acceleration has ceased, to insure that it has moved a sufficient distance from the point of firing to be safe to the using personnel in the event that the fuze is so defective that it will detonate immediately on attaining the armed position. This is accomplished by the described structure, since detent 25 blocks completion of the arming as long as weight 20 is in the setback position. When the setback force on weight 20 has diminished to the point where spring 21 can return weight 20 to its initial forward position, then detent 25 moves out of the way of gear sector 15 which is rotated, under the action of spring 18 into final armed position, which is effected by detent 19 (Figs. 1 and 7) struck up from plate 28. Fig. 7 shows the final position of the gear sector relative to plate 28.

In this position the arming shaft has revolved the detonator rotor out of the aligned position and the fuze is now ready to function.

It will be seen that the above described construction accomplishes the objects of the invention, but it will be apparent that other mechanical motions and elements than the ones shown could be used to accomplish the same objects within the scope of the invention as defined by the appended claims.

We claim:

1. Safety arming mechanism for a projectile fuze of the type having an out-of-line powder train interrupter which is moved into aligned position to arm the fuze, comprising an air driven motor operatively connected with said interrupter to initiate movement thereof toward aligned position, means for releasing the connection of said motor from said interrupter after a predetermined initial motion of said interrupter, and spring means biased to continue said movement of the interrupter into fully aligned armed position.

2. Safety arming mechanism for a projectile fuze of the type having an out-of-line powder train interrupter which is moved into aligned position to arm the fuze, an air driven motor operatively connected with said interrupter for initial movement thereof toward aligned position, means for releasing the connection of said motor from said interrupter after a predetermined initial motion of said interrupter, spring means biased to continue said movement of the interrupter into fully aligned armed position, stop means for preventing said air-driven motor from completing its action, and acceleration-responsive means for disabling said stop means when actu-

ated by the acceleration forces of setback resulting from normal discharge of the projectile.

3. Safety arming mechanism for a projectile fuze of the type having an out-of-line powder train interrupter which is rotated into aligned position to arm the fuze, an air driven motor operatively connected with said interrupter for initial movement thereof toward aligned position, means for releasing the connection of said motor from said interrupter after a predetermined initial motion of said interrupter, spring means biased to continue said movement of the interrupter into fully aligned armed position, stop means for preventing said spring from completing its action, and acceleration responsive means for rendering effective said stop means when actuated by the acceleration forces of normal setback, and responsive to cessation of said setback to disable said stop means and thereby enable completion of arming of the fuze.

4. Safety arming mechanism for a projectile fuze of the type having an out-of-line powder train interrupter which is rotated into aligned position to arm the fuze, an air driven motor operatively connected with said interrupter for initial movement thereof toward aligned position, means for releasing the connection of said motor from said interrupter after a predetermined initial motion of said interrupter, spring means biased to continue said movement of the interrupter into fully aligned armed position, first stop means for preventing said air-driven motor from completing its action, acceleration-responsive means for disabling said stop means when actuated by the acceleration forces of setback resulting from normal discharge of the projectile, second stop means for preventing said spring means from completing its action, and acceleration responsive means for rendering effective said second stop means when actuated by the acceleration forces of normal setback, and responsive to cessation of said setback to disable said second stop means and thereby enable completion of arming of the fuze.

5. The invention, as recited in claim 4, wherein said air-driven motor comprises a wind vane, a shaft driven thereby, a reduction gear train driven by said shaft, a gear sector driven by said gear train, a second shaft rotated with said gear sector and a powder train interrupter rotated by said shaft.

6. The invention, as recited in claim 5, wherein said gear sector is proportioned to be disengaged from said gear train after partial rotation of said second shaft and said spring means includes a spring tensioned to complete rotation of said second shaft after said disengagement.

7. The invention, as recited in claim 6, wherein said acceleration responsive means comprises an inertia weight, said first stop means being held thereby into the path of said gear sector and effective to prevent disengagement of said gear sector and gear train in the normal position and movable by said inertia weight under the force of normal setback out of said path to permit further movement of said gear sector under force of said spring.

8. The invention, as recited in claim 7, wherein said second stop means comprises a second stop held by said inertia weight in the path of said gear sector to prevent said gear sector from fully completing its arming rotation when said inertia weight is in its setback position, but movable by said inertia weight out of said stopping position upon the cessation of setback.
